VALVE LIFTER

Filed March 5, 1929

Inventor:

Otto Blomberg,

By Wilkinson, Husley, Byron & Knight
Attn: G.

UNITED STATES PATENT OFFICE

OTTO BLOMBERG, OF CHICAGO, ILLINOIS

VALVE LIFTER

Application filed March 5, 1929. Serial No. 344,171.

This invention relates to a valve lifter. One object of the invention is to provide a valve lifter by means of which the valve may be raised from its seat to make possible the loosening of a tight valve spring collar.

Another object is to provide a valve lifter whereby the valve may be lifted in an easy and simple manner for examining and renewing the tappet screws.

10 Another object is to provide a practical valve lifter having a selective arrangement of parts whereby the lifter is adapted for universal use on motors of various sizes and styles.

15 Another object is to provide a valve lifter in which the various operative parts cooperate to provide a balanced action and in which the lifter when moved beyond a given point will remain in any adjusted position when 20 released.

Another object is to provide a valve lifter to meet the various requirements for the intended use.

These and other objects are accomplished 25 by means of the arrangement disclosed on the accompanying sheet of drawings, in which—

Figure 1 is a side elevation of the valve lifter, shown in operative association with valve mechanism of an internal combustion 30 engine;

Figure 2 is an end view of the same valve lifter;

Figure 3 is a sectional view taken in the plane of line 3—3 of Figure 1; and

35 Figure 4 is a detailed enlarged view of fastening means for some of the adjustable parts.

The various novel features of the invention will be apparent from the following description and drawings, and will be particularly 40 pointed out in the appended claims.

Referring to the figures of the drawings, it will be noted that my valve lifter includes a relatively stationary main body member having a vertical leg 10 and a horizontal leg 45 11. Slidably or movably mounted with respect to the main body member 10 is a horizontally extending member 12 having adjustably and detachably connected to its outer end an extension member 13, the outer 50 end of which is forked at 14 to straddle the

lower end of the associated valve stem 15, and more particularly, to underlie the valve spring washer 16. The inner end of the movable member 12 is secured at 17 and 18 to a slide member 19 which embraces and is slidably mounted upon the vertical leg 10 of the main body member. A link 20 at its lower end is connected at 18 to the slide 19 and the upper end of said link 20 at 23 is connected to the spaced arms 21 of a hand lever 22. By 55 actuating the hand lever 22 from the dotted line position to the full line position shown in Figure 1, the movable member 12 of the lifter will be raised for compressing the spring 24 surrounding the valve stem 15.

The forward end of the horizontal leg 11 of the lifter is provided with an extension 25 having a plurality of openings 26, 27 and 28. Mounted in the first opening is a valve engaging member 29, the lower end of which is pointed for engaging a complementary part in the upper part of the associated valve 30. Not only is the valve engaging member 29 slidably mounted within the opening 26, but it is also slidably mounted within an 70 elongated groove 31 of a bolt 32 which may be drawn and tightened by a wing nut 33 mounted upon its threaded end for regulating the frictional gripping action of said bolt upon the rod 29. It is intended that the 75 rod 29 shall have a slipping movement in the relatively stationary member of the lifter to permit the whole valve 30 to move upwardly, as the spring 24 is compressed, in the event that the valve spring collar 16 is rusted or otherwise stuck to the valve spring segmental 80 collar key 34 which is mounted within a reduced portion or groove 35 in the valve stem 15. Also by permitting the rod 29 to yield, 85 distortion of the valve lifter is prevented.

It is necessary to have a fixed fulcrum for the tool. In this connection, there is provided a fulcrum including a saddle-shaped member 36 which overlies the valve 30 and having 90 an aperture through which the rod 29 extends. Extending upwardly from the saddle is a rod or holder 37 which extends through the opening 27 in the stationary valve lifter member and which is secured in fixed posi- 100

tion with respect to said member by a lock bolt 38.

As shown in full lines in Figure 1, the lever 22 has been moved into a position to 5 raise the relatively movable valve lifter member 12 for compressing the valve spring 24. Normally the bottom of the valve stem would remain in engagement with the head of the associated tappet screw 39, but if the spring 10 collar 16 is rusted to the valve spring collar key 35, not only will the valve spring 24 be compressed but the valve will move upwardly, provided the rod 29 is permitted to yield under pressure. This the rod is adjusted to 15 do. With the valve 30 thus raised, it will be apparent that the rusted collar 16 and the valve spring collar key 35 may be separated by delivering a blow upon the head 40 of the rod 29 whereupon the segmental valve spring 20 collar key 24 may be removed from the stem and the other parts dissociated.

By this same arrangement, the valve spring may be compressed, leaving the valve in a free or floating position so that the tappet nuts 41 25 and tappet screw 39 may be adjusted, removed and renewed.

As shown, the valve lifter is associated with an internal combustion engine 42 having a manifold 43 extending outwardly quite a 30 distance from the body of the engine 42. Under such circumstances, it will be noted that the extension member 13 is just substantially at its outer position and the rod 29 occupies the outermost opening 26 in the 35 extension member 25. If the manifold 43 does not extend so far out, it will be appreciated that extension member 13 may be adjusted to a position inwardly from that shown and the rod 29 transferred from the hole 26 to the hole 28, in which event the saddle 36 40 will be swung through an angle of 180° so that the opening 44 will be in a position to receive the rod 29 when it is releasably locked in the opening 28. This makes the tool universal for manifolds having various sizes.

There may be various modifications of the invention as herein particularly shown and described, and it is my intention to cover all 55 such modifications which do not involve a departure from the spirit and scope of the invention as defined in the following claims.

I claim:

1. A valve lifter comprising two supported 60 relatively movable members, one of said members being engageable under the valve spring, means yieldably associated with the second 55 of said members and engageable with the valve for permitting the valve to move away from its seat as the valve spring is being compressed, and means associated with said second member for holding the latter in a fixed 65 leverage position regardless of movement of said means engageable with said valve.

2. A valve lifter comprising two supported 70 relatively movable members, one of said

members being engageable under the spring, a rod frictionally held with respect to the second of said members and engageable with the valve for permitting the valve to move away from its seat as the spring is being compressed, and means associated with said second member for holding the latter in a fixed leverage position regardless of movement of said rod with respect to said second member.

3. A valve lifter comprising two supported 75 relatively movable members, one of said members being engageable under the valve spring, a rod releasably and frictionally held in the second of said members and engageable with the valve for permitting the valve to move away from its seat as the spring is being compressed, and means whereby said second member is held in a fixed leverage position regardless of movement of said rod.

4. A valve lifter comprising two supported 80 relatively movable members, one of said members being engageable under the valve spring, a rod releasably and frictionally held in the second of said members and engageable with the valve for permitting the valve to move away from its seat as the spring is being compressed, and a leverage 85 member carried by said second member for holding the latter in a fixed leverage position regardless of movement of said valve engaging rod.

5. A valve lifter comprising two supported 90 relatively movable members, one of said members being engageable under the valve spring, means yieldably associated with the second 95 of said members and engageable with the valve for permitting the valve to move away from its seat as the valve spring is being compressed, means associated with said second member for holding the latter in a fixed 100 leverage position regardless of movement of said means engageable with said valve, and means for adjusting the initial position of said valve engageable means.

6. A valve lifter comprising two supported 105 relatively movable members, one of said members being engageable under the valve spring, means yieldably associated with the second 110 of said members and engageable with the valve for permitting the valve to move away from its seat as the valve spring is being compressed, means associated with said second member for holding the latter in a fixed leverage position regardless of movement of said means engageable with said valve, and means for adjusting the position of said holding means for determining the fixed 115 leverage position.

7. A valve lifter comprising two supported 120 relatively movable members, one of said members being engageable under the valve spring, means yieldably associated with the second 125 of said members and engageable with the valve for permitting the valve to move away from its seat as the valve spring is being com-

pressed, means associated with said second member for holding the latter in a fixed leverage position regardless of movement of said means engageable with said valve, means for adjusting the initial position of said valve engageable means, and means for adjusting the position of said holding means for determining the fixed leverage position.

8. A valve lifter comprising two supported relatively movable members, one of said members being engageable under the spring, a rod releasably and frictionally held in the second of said members and having one end thereof engageable with the valve for normally holding the valve down when the spring is being compressed but which under excessive pressure moves in said second member to permit the valve to move away from its seat, and means associated with said second member for holding the latter in a fixed leverage position regardless of movement of said rod in said second member.

9. A valve lifter comprising two supported relatively movable members, one of said members being engageable under the valve spring, means yieldably associated with the second of said members and engageable with the valve for permitting the valve to move away from its seat as the valve spring is being compressed, and means associated with said second member for holding the latter in a fixed leverage position regardless of movement of said means engageable with said valve, said second member being provided with means whereby said valve engaging means may be selectively mounted with respect to said second member for application of said valve lifter to engines of different sizes and styles.

10. A valve lifter comprising two supported relatively movable members, one of said members being engageable under the valve spring, means yieldably associated with the second of said members and engageable with the valve for permitting the valve to move away from its seat as the valve spring is being compressed, said second member being equipped to selectively receive said valve engaging member whereby the valve lifter may be used with engines of different sizes and styles.

11. A valve lifter comprising two supported relatively movable members, one of said members being engageable under the valve spring, the second of said members having a plurality of attaching portions, means yieldably and selectively associated with the attaching means of aid second member and engageable with the valve for permitting the valve to move away from its seat as the valve spring is being compressed.

12. A valve lifter comprising two supported relatively movable members, one of said members being engageable under the valve spring, the second of said members having a plurality of attaching portions,

means yieldably and selectively associated with the attaching means of said second member and engageable with the valve for permitting the valve to move away from its seat as the valve spring is being compressed, and means associated with said second member for holding the latter in a fixed leverage position regardless of movement of said valve engaging means.

13. A valve lifter comprising two supported relatively movable members, one of said members being engageable under the valve spring, means yieldably associated with the second of said members and engageable with the valve for permitting the valve to move away from its seat as the valve spring is being compressed, and means associated with said second member for holding the latter in a fixed leverage position regardless of movement of said means engageable with said valve, said holding means having a guide portion through which said valve engaging means extends.

14. A valve lifter comprising two supported relatively movable members, one of said members being engageable under the valve spring, the second of said members having a plurality of attaching portions, means yieldably and selectively associated with the attaching portions of said second member and engageable with the valve for permitting the valve to move away from its seat as the valve spring is being compressed, means associated with said second member for holding the latter in a fixed leverage position regardless of the movement of said valve engaging means and being adjustable in position for guiding said valve engaging means regardless of the selective position of the latter.

Signed at Chicago, Illinois, this 25th day of February, 1929.

OTTO BLOMBERG.
